(57) **CLAIM**

The ornamental design for a floating device for human relaxation on water, as shown and described.

DESCRIPTION

FIG. 1 is a right side view of a floating device for human relaxation on water shown as a new design;

FIG. 2 is a left side view thereof;

FIG. 3 is a front side view thereof;

FIG. 4 is a back side view thereof;

FIG. 5 is a top view thereof; and,

FIG. 6 is a bottom view thereof.

The broken lines in the drawing are for illustrative purposes only and form no part of the claimed design.
